UNITED STATES PATENT OFFICE.

JOHN G. SCHUIRMANN, OF KENT, WASHINGTON, ASSIGNOR OF ONE-HALF TO CHARLES L. SANTEE, OF RENTON, WASHINGTON.

ELECTRICALLY-HEATED PAD AND THE LIKE.

1,074,216.

Specification of Letters Patent. Patented Sept. 30, 1913.

Application filed May 20, 1912. Serial No. 698,611.

To all whom it may concern:

Be it known that I, JOHN G. SCHUIRMANN, a citizen of the United States of America, and a resident of the town of Kent, in the county of King and State of Washington, have invented certain new and useful Improvements in Electrically-Heated Pads and the like, of which the following is a specification.

10 My invention has particular reference to electrically heated pads, and a primary object thereof is to provide a device of this character wherein the heating element is so constructed and supported as to permit 15 of the pad being folded and thereby reduced to compact form when not in use, without injury to the heating element.

With the above and other objects in view to be referred to as my description progresses, my invention resides in the features 20 of construction, arrangements and combinations of parts hereinafter described and succinctly defined in my annexed claim.

Referring to the accompanying drawing 25 wherein like numerals of reference indicate like parts throughout: Figure 1 is a plan of a pad constructed in accordance with my invention, portions of the covering and facing being broken away. Fig. 2 is a section taken on line 2—2 of Fig. 1, and Fig. 3 is a detail illustrating in section the joint between one of the heating element sections and the relatively flexible or pliable connecting wires.

30 In carrying out my invention I provide the resistance wire or element, in sections, as 1, 2, 3 and 4, said element being connected as at 1', 2', with the leading wires 5 and 6 adapted to connect the heating element 35 with a suitable source of electrical energy, and the sections being joined at their adjacent ends by relatively flexible or pliable wires 7. Insulations 7' are provided about the connection between pliable wires 7 and 40 the resistance wires and also serve as members for spacing the cover sections 8 from

the heating element, as is clearly shown in Fig. 2. One of the flexible joining wires 7 lies directly opposite wires 5 and 6, thereby permitting of the heating element sections 50 on one side being swung or positioned over those on the opposite side thereof. The other joining wires 7 are directly opposite one another.

Reference numeral 8 indicates a covering 55 member for the resistance element, the same comprising flexible side members to one of which the resistance element sections 1, 2, 3 and 4 are secured, as by stitches 9.

Reference numerals 10 indicate facing 60 members of any suitable flexible material which are secured to the covering member 8 and to an edge strip 11, as by sewing.

Resistance element sections 1, 2, 3 and 4 are preferably formed of wire, commonly 65 known as "nicrom", and being secured to but one of the side members of covering 8 and connected to one another, by the flexible joining wires 7, which are conveniently of copper, will be uninjured by folding and 70 unfolding of the pad, as will be apparent.

Having thus described my invention what I claim as new, and desire to secure by Letters Patent of the United States of America, 75 is:

In a device of the character described, a covering member comprising independent side sections, a heating element in said covering member comprising resistance wire sections, flexible joints connecting the sections in series, and enlarged insulating members covering the connection of said flexible joints to the resistance wire sections and spacing the side sections of said covering member from the heating element. 80 85

Signed at Seattle, Washington, this 2nd day of May, 1912.

JOHN G. SCHUIRMANN.
